FLATIRON

Fred Goldfisher, Chicago, Ill.

Application October 26, 1939, Serial No. 301,496

6 Claims. (Cl. 38—77)

My invention relates to flatirons, and more particularly to means for dispensing steam during the use of the same, and my main object is to provide a steam dispensing attachment which is applicable to any type of flatiron, whether plain, or operated by kerosene, gas or electricity.

A further object of the invention is to incorporate an automatic control in the novel attachment which will cause steam to be dispensed only when the iron has attained a sufficient heat to assure the vaporization of the feed-water employed to produce the steam.

A still further object of the invention is to provide an attachment of the above character which is in the form of a base plate receiving the flatiron over it, such base plate containing the means for dispensing the steam.

Another object of the invention is to construct the attachment with securing means applied over the flatiron and adjustable to variations in the height and form thereof.

An additional object of the invention is to incorporate a small feed-water reservoir for the steam supply at a point clear of the flatiron and not in the way when the same is being used.

An important object of the invention is to design the novel attachment along lines of simplicity and ease of application, whereby to render its production economical and its use handy.

With the above objects in view and any others which may suggest themselves from the description to follow, a better understanding of the invention may be had by reference to the accompanying drawing, in which—

Fig. 1 is an elevation of a typical flatiron, showing the attachment applied;

Fig. 2 is a top plan view of the attachment; and

Figs. 3 and 4 are, respectively, sections on the line 3—3 and 4—4 of Fig. 2.

Electric irons capable of generating steam have been developed and marketed in late years, but such irons are quite expensive because of their special construction and therefore beyond the means of the average user. Further, where electricity is not readily available or too costly, flatirons using gas or kerosene for fuel are employed, these presenting little or no prospect for development to dispense steam. It has therefore been my intention to provide a unit which converts any flatiron into a steam dispensing one, enabling users of all types of flatirons to benefit from this improvement.

In accordance with the foregoing, specific reference to the drawing indicates a typical flat-

iron at 10. The illustration is of an electric flatiron, but it goes without saying that any other type will serve the purpose.

The attachment primarily involves a flat plate 11 doubled with a top section 12, the plate having the general outline of a flatiron and a guard rim 13 to receive a flatiron of substantially similar form.

A short distance behind the plate 11 is an elevated miniature tank 14, companion tubes 15 leading from the bottom of the tank over the zone of the plate to a post 16 erected at the front of the latter. The object of the tubes 15 is to lead water from the tank into the post 16. The tubes follow courses immediately over the flatiron, whereby to receive heat therefrom and cause the water to vaporize when it reaches the post 16. The latter is actually a miniature housing and has an outlet at the bottom into a rearward duct 17 which is formed by pressing the top 12 of the plate 11 slightly upward along a medial course. The said top is also pressed to extend the duct 17 with a cross duct 18 at the rear and outward return ducts 19 at the sides. The steam emerging from the housing 16 thus takes a course according to the dotted-line arrows in Fig. 2 and emerges from the bottom of the iron by way of fine perforations 20 made therein at points in the forward portions of the ducts 19.

The housing 16 is primarily intended to contain a control for the passage of the contents in the tubes 15. Thus, the user could wait until the flatiron is hot before releasing the control in the housing 16, but I have made this feature automatic in order to relieve the user of any concern or attention in this respect. The control provided is therefore thermostatic and so designed that it will not release the contents of the tubes 15 until they have attained vaporized form, thus precluding the premature release thereof and the wetting of the material on which the iron is used.

A typical thermostat design for the housing 16 is indicated in Fig. 4. It is seen that the tubes 15 enter a chamber 16a in which an upstanding tube 21 is located. This tube is ordinarily closed by a valve 22 whose stem 23 is held down by a blade 24 of bi-metal which is secured to the top 12 of the plate 11. Since the flatiron rests upon said top, the blade 24 will flex upwardly at a prescribed temperature, opening the valve 22. Water vapor from the tubes 15 thus passes through the housing 16 into the duct 17; and the latter being in direct contact with the bot-

tom of the flatiron and therefore very hot, it follows that the progress of the vapor in the duct 17 sidewise through the duct 18 and forward in the ducts 19 will result in the discharge of steam by way of the perforations 20.

In order that the attachment may be made fast to the flatiron for purposes of support as well as heat-contact, I have designed the tubes 15 to also serve as straps or clamps. Thus, the front ends of the tubes enter the side receptacles 16b of the housing 16 freely, but with a snug fit whereby to pivot the tubes from the housing. The tank 14 and the tubes 15 can thus be swung upwardly to permit the insertion of the flatiron and then lowered upon the same to the position indicated in Fig. 1. The plate 11 is formed with lateral standards 25 at the rear, these having a vertical series of inclined lugs 26 on the inner sides. As the tubes 15 are somewhat flexible, the same may trip over the top or a lower pair of the lugs 26 until they seat over the flatiron, according to the height of the latter. The standards 25 are also flexible strips, and capable of being spread to the extent of releasing the tubes in case these are again to be raised. The tubes 15 are preferably of the familiar copper or brass round type, but they may be designed in flat or other form for adaptation to the form of the iron, or for compactness or heat contact. Also, the manner of securing the tubes in the clamped form may also be different, the devices indicated being more for purposes of example. It follows that the supply tank 14 may also be changed in form, size or position to suit the particular situation.

It will be evident from the above description that I have provided an attachment which at once converts any flatiron into a steam dispensing iron. This is done without in the least changing, modifying or adding to the flatiron, or fitting the latter with any attaching means. The attachment can thus be purchased and applied to any iron of commensurate size without work or attention other than to open it, insert the iron and adjust the clamp, at which time the flatiron at once becomes a steam dispensing iron in the fullest sense of the word. As previously described, the passage of the water over the top of the flatiron may result in the generation of steam. The passages 15, however, need not be depended upon for this purpose since any remaining water will be evaporated in generator 17, as long as the sole plate temperature is high enough to maintain valve 22 open. The attachment is therefore proof against the leakage of water or condensed vapor, as only steam can pass to the zone of issue, such passage being along the hottest course. The attachment is therefore safe and fully automatic. Further, the plate 11 is formed with its ducts by the simple pressing of its tube 12, so as to employ no extra parts which may get out of adjustment and cause leakage. Finally, it is apparent that the attachment is constructed with the fewest number of parts consistent with its proper design and operation, whereby to be manufactured economically and be capable of handling and use with facility.

While I have described the invention along specific lines, various minor changes and refinements may be made without departing from its principle, and I desire to consider all such changes and refinements as come within the scope and spirit of the appended claims.

I claim:

1. An attachment for flatirons comprising a steam generator formed as a base to support the flatiron, a water container, a water feed for said generator comprising supply conduits leading from the container over the flatiron to connect with the generator, and means interposed between the base and the conduits to hold the latter in clamping engagement with the flatiron.
2. The structure of claim 1, said conduits being flexible and responsive to said means to lie in contact with the flatiron substantially along their entire course over the same.
3. An attachment for flatirons comprising a steam generator formed as a base to support the flatiron, a water container at one end of the generator, a water feed for the generator comprising supply conduits leading from the container over the flatiron to connect with the generator at its other end, the connection of the conduits and the generator being a horizontal pivot, standards rising from the generator alongside the conduits at said first-mentioned end, and vertically-spaced pairs of stops carried by the standards and selectively engageable by the conduits according to the height of the flatiron to clamp the conduits upon the same.
4. The structure of claim 3, the conduits being flexible whereby the stops may be chosen to impart a tension to the conduits and the clamping action thereof.
5. An attachment for flatirons, comprising a steam generator formed as a base to support the flatiron and having the outline of the latter with a pointed front, a water container, a water feed for said generator comprising supply conduits leading from the container over the flatiron to connect with the generator, and a thermostatic valve between the conduits and said end of the generator and in a position such that it is responsive to the temperature of the point of the flatiron and adapted to be opened when the flatiron rises above a predetermined temperature.
6. An attachment for flatirons, comprising a steam generator formed as a base to support the flatiron and having the outline of the latter with a pointed front, a water container, a water feed for said generator comprising supply conduits leading from the container over the flatiron to connect with the generator, and a thermostatic valve between the conduits and said end of the generator and in a position such that it is responsive to the temperature of the point of the flatiron and adapted to be opened when the flatiron rises above a predetermined temperature, said valve having an upstanding casing, and the latter having receptacles on opposite sides to receive the connecting portions of the conduits.

FRED GOLDFISHER.
